UNITED STATES PATENT OFFICE

CHARLES D. VARY, OF ELGIN, ILLINOIS

DESIGN FOR A PORTABLE GASOLINE-FILLING-STATION BOOTH

Application filed April 28, 1930. Serial No. 35,408. Term of patent 7 years.

To all whom it may concern:

Be it known that I, CHARLES D. VARY, a citizen of the United States, residing at Elgin, in the county of Kane and State of Illinois, have invented a new, original, and ornamental Design for Portable Gasoline-Filling-Station Booth, of which the following is a specification, reference being had to the accompanying drawing, forming part thereof.

Fig. 1 is a perspective view of a filling station, showing my new design.

The side opposite that shown in the drawing is identical therewith.

I claim:—

The ornamental design for a portable gasoline filling station booth, as shown and described.

CHARLES D. VARY.
